CORRUGATING DIE

James A. Watt and Alfred J. Perkins, Buffalo,
N. Y., assignors to Curtiss-Wright Corporation,
a corporation of Delaware

Application March 9, 1944, Serial No. 525,788

4 Claims. (Cl. 153—76)

This invention relates to improvements in corrugating dies and, although not necessarily limited to such use, is characterized by features which render it of particular utility in connection with the formation of straight-sided corrugations.

Corrugating dies, as heretofore proposed, have the objection that when utilized in connection with the annealed sheets, the subsequent heat treatments to which the latter are subjected for hardening purposes cause warping of the sheets and thereby render it difficult, and in many instances impossible, to maintain the required tolerances. On the other hand, when the sheets are pre-hardened and a brake employed to form the corrugations it is even more difficult to maintain the required tolerances. Regardless of the method employed, therefore, the finished corrugated sheet may be warped or the corrugations thereof may be inaccurately formed.

The principal object of the present invention is to overcome the above objections, this object contemplating dies which are available for use in connection with the corrugating of hardened sheets and which when so employed are adapted to form corrugations which are uniform and highly accurate as to dimensions and to the locations between the centers of the crest portions.

A further object is a novel design and arrangement of the dies, whereby to enable the corrugations to be formed rapidly and without stretching, thinning, stressing or marring of the walls thereof.

The invention is illustrated in the accompanying drawings, in which:

Figure 1 is an end elevational view of dies embodying the features of the invention, the dies being shown at the completion of a stroke in which a pilot corrugation is formed.

Figure 2 is a similar view showing the relation of the dies when a side and the bottom of a second corrugation are formed.

Figure 3 is a similar view showing in full lines the relation of the dies just prior to the operation of the latter to form the third corrugation and in dotted lines the open position of the dies.

Figure 4 is a similar view showing the relation of the dies after completion of the stroke in which the third corrugation is formed.

Figure 5 is a fragmentary elevational view, partially in section, of the entrance side of the die set.

Figure 6 is a similar view also partially in section, of the opposite side of the die set.

Figure 7 is a detail sectional view.

The dies are illustrated in connection with a

power press which is sufficiently indicated for the purpose in view by a showing of the bed 10 and ram 11 thereof. A punch assembly 12 is carried by the latter. The said assembly, which includes elongated, parallel punch elements 13, 14 and 15, also includes a holder 16, the latter being carried by parallel bars 17 which are secured to the ram 11 by clamps 18. The punch element 14 and an angle member 19 which are suitably secured together as a unit are connected to the holder 16 by bolts 20 (Figure 1), the said unit being normally held in the extended position shown in Figure 3 by springs 21. The punch element 14 and angle member 19 carry the punch element 15 either in an operative, or extended, position or in an inoperative, or retracted, position. To this end a bar 22 which is suitably secured to the overhanging flange on the punch element 14 is formed with a series of spaced lugs 23. The latter cooperate with a similar series of lugs 24 formed on the top of the punch element 15, the lugs 23 being adapted either to provide seats for the lugs 24 or to accommodate the latter in the spaces between them. When the lugs 23 are utilized as seats the punch element 15 is held in its extended position, being locked in such position by pins 25 which are accommodated in aligned holes formed for this purpose in the angle member 19 and in the punch elements 14 and 15. By removing the pins 25, shifting the punch element 15 lengthwise and then elevating it, the lugs on the punch element may be caused to register with and enter the spaces between the lugs on the bar 22. The punch element 15 is thereby withdrawn to an inoperative position in which it may be locked by the pins 25.

The punch element 13 is suspended from the holder 16 in a position alongside the punch element 14 by a bar 26. The latter may be secured to the holder by a key 27 and bolts 28 either in a position to hold the punch element 13 in an extended, or operative, position or in a retracted, or inoperative position, the bar 26 being formed with slots 29 (Figure 5) for accommodating the bolts 28 in either position of said bar. Backing blocks 30 are preferably employed in connection with the bar 26, being arranged between the latter and the bars 17 when the punch element 13 occupies its extended position. When the said element is to be withdrawn to its retracted position, the blocks 30 are moved to one side, as indicated in dotted lines in Figure 5, so that they may enter the spaces between the bars 17.

The punch element 13 is pivotally connected to the bar 26 by a shaft 31. The latter is journaled in a bearing 32 which is formed in the underside

of the bar 26, being secured therein by caps 33 and being formed with half-round sections 34 to which the punch element is secured by bolts 35. The shaft 31 supports the punch element 13 so that it may swing either to a position in which it contacts the side of the punch element 14 or to the angular position shown in Figure 3. The punch element 13 is biased to the latter position by spring-loaded pins 37 which are carried by the former and which act against the adjacent side wall of the punch element 14. Outward movement of the punch element 13 in response to the spring-loaded pins 37 is limited by engagement of an angularly inclined shoulder 39 on the said element with the underside of the bar 26.

A die member 40 cooperates with the punch assembly described. The said member (Figure 3) is normally supported above a bed plate 41 by air-actuated plungers 42, the said bed plate resting on the bed 10 of the press and carrying guides 43 which are accommodated in bores 44 formed in the holder 16. The die member 40 may also occupy a position, as shown in Figure 1, in which it is seated on the bed plate 41, suitable means being provided for guiding the die member between the two positions shown while holding it against sidewise and endwise movements.

In the operation of the dies, the ram of the press is actuated to cause the punch element 14 to form a pilot corrugation 45 (Figure 1) in the sheet 46 to be corrugated, the punch elements 13 and 15 being held in their inoperative positions during this operation. After the pilot corrugation has been formed, the ram of the press is elevated to withdraw the punch assembly 12, and without disturbing the sheet 46 the punch element 13 is lowered to and secured in its operative position and the ram of the press again actuated. At this time the punch element 13 moves in front of a guide member 47 and lightly engages the sheet 46 as best shown in Figure 3, while the springs 21 hold the adjacent punch assembly 14 extended as this occurs. Thereafter as the ram continues its working stroke, the plungers 42 support the die member 40 in its elevated position while the springs 21 yield to permit the holder 16 to move toward the punch elements 14 and 15. During this relative movement between the holder 16 and the punch elements 14 and 15, the punch element 13 moves with the holder. As the punch element 13 is actuated in the manner described, a curved wall of the guide 47 acts against it to cause it to swing inwardly toward and against the side wall of the punch element 14 against the action of the spring-loaded pins 37, whereby to form a side wall and the bottom wall of a second corrugation 48, as best shown in Figure 2, it being noted in this connection that the punch element 13 is provided with a hardened steel insert 49 which receives any wearing action to which the said punch element is subjected by virtue of its sliding contact with the guide member 47.

As the side and bottom walls of the second corrugation are formed, the lost motion between the holder 16 and the die elements 14 and 15 is taken up so that thereafter as the ram continues its working stroke all of the elements of the punch assembly 12 and the die member 40 moves as a unit, the pressure acting against the plungers 42 being predetermined to support the said die member against yielding movement until the lost motion between the holder 16 and the die elements 14 and 15 has been wholly taken up. After the punch assembly and die member

have been moved downwardly a predetermined distance by the ram, an angularly inclined wall 50 on the under side of the die member 40 engages an underlying wall 51 of an elongated rotatable member 52. The latter is journaled in spaced bearing blocks 53 (Figure 5) and is normally held in the angular position shown in Figure 3 by springs 54 which at one end are connected to arms 55 carried by the rotatable member 52 and which at their opposite ends are connected to the base plate 41. When the angular wall 50 on the under side of the die member 40 engages the wall 51 of the member 52, the continued movement of the die member causes the member 52 to turn in the bearings 53, whereby a face 56 on the member 52 engages that portion of the sheet 46 which is to form the second side of the second corrugation and bends the said side against the cooperating side face of the punch element 13. As the die member 40 seats on the bed plate 41, a radial portion 57 of the rotatable member 52 engages an end wall 58 of the die member 40. At this time, therefore, the die member 40 and rotatable member 52 form a continuous die cavity in which the punch element 13 completes its forming operation. Thus, although the punch element 13, die member 40 and rotatable member 52 and the sheet material, their final action is that of cooperating male and female dies.

Upon completion of the second corrugation, the ram of the press is retracted to withdraw the punch assembly and permit the elements thereof and the die members 13 and 52 to be restored to their original positions. The punch element 15 is then lowered to, and secured in, its operative position and after the sheet 46 has been advanced to position the pilot corrugation in the die cavity which the punch element 15 is to enter and the second corrugation in the cavity which the punch element 14 is to enter, the ram is again actuated to cause the punch element 13 to form a third corrugation 59, as illustrated in Figure 4, in the same manner in which the second corrugation was formed. Thereafter all of the elements of the punch assembly are employed in each operation of the press.

It will be noted that in the operation of the forming dies, each corrugation, except the pilot corrugation, is initially formed by the punch element 13 and cooperating die members 40 and 52. Each corrugation which is thus formed is thereafter acted upon first by the punch element 14 and then by the punch element 15. In accordance with the invention the punch element 13 forms corrugations having side walls which are flared less than the final angle of flare produced by the punch elements 14 and 15. This has the advantage that a corrugation which has been roughly formed by the punch element 13 will readily enter the die cavity in which the punch element 14 operates and in which it is sized. The sized corrugations are restruck by the punch element 15. Thus after the first two corrugations have been formed each operation of the dies forms a new corrugation, sizes a pre-formed corrugation and restrikes a pre-sized corrugation.

From the foregoing it will be apparent that in corrugating the sheet 46 in the manner described, no portions thereof are subjected to a drawing action, hence there is no thinning or stretching of any of the zones of the said sheet, it being noted in this connection that the punch element 13 initially engages the sheet 46 (see

Figure 3) along a line at which the bend connecting a side wall and the bottom wall of the corrugation will be formed and that this line of contact is maintained as the said punch element moves downwardly and at the same time swings inwardly. There is also very little sliding contact between the sheet 46 and the rotatable member 52. The dies, therefore, have the further advantage that scoring of the sheet as an incident to the forming operations is minimized.

A further advantage obtained is that at the time a corrugation is being formed by the punch element 13, the sheet is firmly gripped between the punch elements 14 and 15 and the die member 48 while the punch element 14 and the said die member provide a straight edge over which the sheet may be bent. As a result of this and the action of the rotatable member 52 in the manner described, the sheet acted upon may be of hardened stock, it being possible with such stock to form corrugations which may be held well within the desired tolerances.

We claim as our invention:

1. In a power press having relatively movable opposed working members, the combination of forming dies for corrugating sheet material including a female die member yieldably carried on one of the working members, companion punch elements carried on the other of said working members, one of which is normally extended and the other of which is normally retracted, said last mentioned punch element being pivotally mounted on said other working member, means for normally holding said last mentioned punch element in an angular relation with respect to said first mentioned punch element, means for advancing said punch elements while holding said die member relatively stationary thereby first to cause said first mentioned punch element to enter a pre-formed corrugation in said material and said last mentioned punch element then to be advanced with respect to, and to be pivoted toward, said first mentioned punch element against the action of said first mentioned means to form part of a second corrugation, said second mentioned means being thereafter operative to cause yielding movement of said die member and advance said punch elements and die member as a unit, and means on said one working member for cooperating with said last mentioned punch element and said die member and responsive to the movement of the latter for forming another part of said second corrugation.

2. In a power press having relatively movable opposed working members, the combination of dies for forming straight-sided corrugations in sheet material including a female die member yieldably mounted on one working member, companion punch elements mounted on another working member, one of which is normally extended and the other of which is normally retracted, said last mentioned punch element being pivotally mounted on said other working member, means for normally holding said last mentioned punch element in an angular relation with respect to said first-mentioned punch element, means for advancing said punch elements while holding said die member relatively stationary thereby first to cause said first mentioned punch element to enter a pre-formed corrugation in said material and said last mentioned punch element then to advance with respect to, and to be pivoted toward, said first mentioned punch element against the action of said first mentioned means to form a

side and the bottom portions of a second corrugation, said second mentioned means being thereafter operative to cause yielding movement of said female die member and advance said punch elements and die member as a unit, and means on said one working member for cooperating with said last mentioned punch element and said die member and responsive to the movement of the latter for forming the other side portion of said second corrugation.

3. In a power press having relatively movable working members, the combination of forming dies for corrugating sheet material including a female die member yieldably mounted on one working member, companion punch elements mounted on the other working member, one of which is normally extended and the other of which is normally retracted, said last mentioned punch element being pivotally mounted on said other working member, means for normally holding said last mentioned punch element in an angular relation with respect to said first mentioned punch element, means for advancing said punch elements while holding said die member stationary thereby first to cause said first mentioned punch element to enter a pre-formed corrugation in said material and said last mentioned punch element to be advanced with respect to said first mentioned punch element, a guide on said one working member for causing said last mentioned punch element to swing toward said first mentioned punch element as it is advanced relatively to the latter, whereby to form a part of a second corrugation, said second mentioned means being thereafter operative to advance said punch elements and die member as a unit, and means on said one working member for cooperating with said last mentioned punch element and said die member and responsive to the movement of the latter for forming another part of said second corrugation.

4. In a power press having relatively movable working members, the combination of dies for forming straight-sided corrugations in sheet material including a female die member yieldably mounted on one of the working members, companion punch elements movably mounted on the other working member, one of which is normally but yieldably extended and the other of which is normally retracted, means for advancing said punch elements while holding said die member stationary, thereby first to cause said first mentioned punch element to enter a pre-formed corrugation in said material and thereafter to yield so that said last mentioned punch element will be in position to form a side wall and the bottom of a second corrugation, said means being thereafter operative to advance said punch elements and yieldable die member as a unit, and sheet material folding means for cooperating with said last mentioned punch element and said die member while they are moving as a unit to fold a portion of the sheet material to form the other side of said second corrugation, said last mentioned punch element, said die member and said folding means cooperating in the forming of the sides of said second corrugation so that the angles that they form with respect to the bottom are sharper than the corresponding angles between the sides and bottom of said pre-formed corrugation after being acted upon by said first mentioned punch element.
